UNITED STATES PATENT OFFICE

CLAUDE E. FURGASON, OF LANSING, MICHIGAN, ASSIGNOR TO REO MOTOR CAR COMPANY, OF LANSING, MICHIGAN, A CORPORATION OF MICHIGAN

SELF-OILING SHACKLE OR HANGER FOR SPRINGS

Application filed October 18, 1926. Serial No. 142,401.

This invention relates to self oiling shackles or hangers for springs and more especially to improvements therein designed to simplify and render such structures more efficient.

The invention has as one of its objects to provide a shackle for springs having an oiling reservoir of some capacity together with means for conducting the oil to the several bearing points as well as to the end thrust members.

The invention also has as one of its objects to provide a construction of this character of a simplified design so that the same may be quickly and economically manufactured and expeditiously assembled.

The several objects, advantages and novel details of this construction will be made more apparent as this description proceeds especially when considered in connection with the accompanying drawings wherein:

Figure 1, is an end elevation of a spring shackle construction in accordance with this invention.

Figure 2, is a vertical sectional view through the shackle.

Figure 3, shows a slightly modified form of construction particularly adapted for use in supporting the front spring of a vehicle, 30 and

Figure 4, is a vertical sectional view through the structure illustrated in Figure 3.

Referring first to Figures 1 and 2 it will be noted that I have fragmentarily illustrated a 35 portion of the frame 10 of the vehicle and a portion of the spring 11. The spring shackle or hanger is indicated generally by the reference character 12 and consists of a pair of complementary sections 13 formed by casting, one of the sections being provided with a reservoir 14 for the lubricant, the open end of which may be conveniently closed by a cap 15. It is obviously preferable that the reservoir 14 be located adjacent the upper end of

40 one of the castings 13 so that the lubricant contained therein may flow by gravity to the several points of distribution.

Associated with the two sections 13 are hanger shafts 16 and 17, the former providing the pivotal connection between the

shackle and frame 10 while the latter provides a means for supporting the end of the spring 11. It is generally customary and desirable to introduce bushings 18 between the shafts 16 and 17 and the elements supported thereby.

The ends of the shafts 16 and 17 extend into recesses 19 formed in the castings 13 and are journaled therein, bushings 20 being preferably located in the recesses 19 for receiving the said ends of the shafts. The end thrusts imparted to the parts are taken up by means of disc-like members or washers 21 arranged in the bottom or ends of the recesses 19. For preventing the escape of oil which might work its way along the shafts 16, gaskets 22 are provided, these gaskets surrounding the shafts 16 and 17 and reposing in recesses 23 provided in the castings 13 for that purpose.

Each of the shafts 16 and 17 is provided with a longitudinally extending bore or passageway 24 and with cross passage-ways 25. These cross passage-ways coincide with apertures 26 formed in the bushings 20, the latter communicating with passages 27 provided longitudinally of each casting 13. Each of the end thrust members 21 is provided with a centrally arranged aperture 28 and in this manner, as clearly illustrated in Figure 2, the lubricant introduced into the reservoir 14 may flow through the several passages and apertures to each of the points in the structure which require lubrication. The apertures 28 arranged in the end thrust members 21 permits these members to be enclosed in a film of oil thus minimizing the effects of any end thrusts to which the parts are subjected. Obviously the lubricant flows first into the bore 24 of the shaft 16 and then through cross passages 25 and apertures 26 into the passages 27 formed in the castings 13 and from these latter passages into the bore and cross passages of the lower shaft 17.

As previously described the shackle or hanger comprises two complementary castings 13, each of which is provided with a sleeve-like extension or projection 29 which in the assembled position of the parts are opposed with the end faces thereof abutting. Thus the two shackle parts 13 may be con-

veniently united by means of a clamp bolt 30 extending transversally through the two castings and secured in place by nuts 31. The clamping pressure exerted by the bolt and nuts is resisted by the two castings 13, the length of the extensions 29 being so selected that when the parts are assembled and secured in position, as illustrated in Figure 2, a clearance is provided between the ends of the vehicle frame and spring and the adjacent faces of the castings 13.

If it is found desirable, gaskets or the like 32 may be interposed between the nuts 31 and the adjacent faces of the castings 13 while a gasket or packing member 33 may also be provided around the bolt 30 at the abutting faces of the extensions 29. While these last described gaskets or packings are usually found to be unnecessary they, nevertheless, will insure the absence of any leakage of the lubricant along the bolt 30.

It is obviously a simple matter to assemble the shackle as the shafts 16 and 17 may be engaged respectively with the frame 10 and the spring 11 whereupon the two castings 13 may be engaged with the projecting ends of these shafts and secured together as a unit by means of the bolt 30 and nuts 31. When thereafter the reservoir 14 and as a consequence the several passages are filled with lubricant it has been found that the shackle does not need further attention, insofar as lubrication is concerned, for many months, the oil flowing as needed to the several bearing points until the entire supply is exhausted.

In Figures 3 and 4 a slightly modified construction is illustrated, the reference character 10' indicating the frame of the vehicle and 11' the end of the spring. This structure is particularly designed for supporting the end of the front spring of the vehicle and comprises a main casting indicated generally by the reference character 34 and a pair of complementary castings or cap-like members 35. The casting 34 is formed with a bracket portion 36 secured as at 37 to the frame 10' and with a hanger or supporting portion 38. The opposed faces of the castings 34 and 35 are formed with semi-circular recesses to receive and accommodate bearing members 39. The castings or cap members 35 are secured in place with reference to the casting 34 by means of bolts 40.

The bearing members 39 are cup-shaped and are each provided with a laterally extending peripheral flange 41 which seats in an annular recess formed in the castings 34 and 35. This prevents axial displacement of the bearing members when the two castings are united by the bolts 40. A hanger shaft 42 is employed, the ends of which are journaled in the bearing members 39. Gaskets 43 surround the shaft 42 and are arranged in recesses formed in the peripheral faces of the

bearing members 39. A bushing 18' will preferably be provided between the spring 11' and the shaft 42. One of the bearing members 39 is apertured and connected thereby to the lubricant reservoir 44. The shaft 42 is provided with a longitudinally extending bore 45 and cross passages 46. Thrust members 47 are also arranged at the ends of the shaft 42 in the same manner as previously described.

Obviously lubricant introduced into the reservoir 44 will flow to the several points where the presence of lubricant is desired and as in the previously described construction the thrust members 47 will be enclosed in a film of oil with the described advantageous results. The assembling of this form of the invention may also be accomplished with ease and facility as will be readily apparent. After the shaft 42 has been connected with the end of the spring the bearing members 39 may be engaged with the ends thereof whereupon the castings or cap members 35 may be secured in place to lock the several parts together.

While in the preceding description two embodiments of the invention have been described somewhat in detail it will be at once readily apparent that the invention is capable of numerous changes in many of the essential and all of the non-essential details without departing from the spirit and scope thereof, and to this end reservation is made to make such changes as may come within the purview of the accompanying claims.

What I claim as my invention is:

1. In a hanger for vehicle springs, a body member, a hanger shaft journaled therein, disk like end thrust members flatly engaged by said body member and the ends of said shaft, a lubricant reservoir, said shaft and thrust members being formed with communicating passages connected to said reservoir whereby lubricant is conducted to the bearings of said shaft and the thrust members therefor.

2. A hanger for vehicle springs comprising a pair of sections having recessed terminals provided with closed outer sides, bushings in said recessed terminals, shafts journaled in said bushings, said sections, said bushings, and said shafts being provided with communicating passages for conducting a lubricant to the bearings for said shafts, thrust members flatly engaged by the ends of said shafts and the closed ends of said recessed terminals and being provided with lubricant passages communicating with said first-named passages, and a lubricator carried by one of said recessed terminals and having communication with said lubricant passages.

3. A hanger for vehicle springs comprising a pair of sections having recessed terminals provided with closed outer sides, bush-

ings in said recessed terminals, shafts journaled in said bushings, said sections, said bushings, and said shafts being provided with communicating passages for conducting lubricant to the bearings for said shafts and to provide for a complete circulation of the lubricant through said sections, said bushings and said shafts, and means for supplying a lubricant to said passages.

4. A hanger for vehicle springs comprising a pair of complementary sections having their corresponding end portions arranged in spaced relation and provided with cooperating bearings, shafts journaled in said bearings, said sections and said shafts having communicating passages for conducting lubricant to the bearings for said shafts and to provide for the circulation of the lubricant between said sections and said shafts, and means for supplying lubricant to said passages.

5. A hanger for vehicle springs comprising a pair of complementary sections having their corresponding end portions arranged in spaced relation and provided with cooperating bearings, shafts journaled in said bearings, said sections and said shafts having communicating passages for conducting lubricant to the bearings for said shafts and to provide for the circulation of the lubricant between said sections and said shafts, and a lubricator carried by one of said sections for supplying a lubricant to said passages.

6. A hanger for vehicle springs comprising a pair of complementary vertically disposed sections having their corresponding upper and lower end portions arranged in spaced relation and provided with cooperating bearings, shafts journaled in said bearings, said sections and said shafts having communicating passages for conducting lubricant to the bearings for said shafts and to provide for the circulation of the lubricant between said sections and said shafts, and a lubricator formed integral with one of said sections adjacent the upper end thereof for supplying lubricant to said lubricant conducting passages.

In testimony whereof I affix my signature.

CLAUDE E. FURGASON.
